Application April 14, 1949, Serial No. 1,975

Term of patent 14 years

(Cl. D61—1)

To all whom it may concern:

Be it known that I, Oswald C. Hollstein, a citizen of the United States, residing at 780 Second Street, Secaucus, New Jersey, have invented a new, original, and ornamental Design for an X-ray Apparatus, of which the following is a specification, reference being had to the accompanying drawing, forming part thereof.

The figure is a perspective view of an X-ray apparatus, showing my new design.

The essential features of my design reside in the parts shown in full lines.

I claim:

The ornamental design for an X-ray apparatus, as shown and described.

OSWALD C. HOLLSTEIN,
